PIN FEED PLATEN ROLL

John Q. Sherman, Dayton, Ohio

Application December 7, 1933, Serial No. 701,307
In Great Britain July 22, 1933

64 Claims. (Cl. 197—133)

This invention relates to writing machines, and more particularly to paper feeding means for feeding superposed record sheets and interleaved carbon sheets circumferentially about a 5 cylindrical platen, and maintaining such sheets in accurate registry at the writing line. This application is a continuation in part of my co-pending application Serial No. 542,855 filed June 8, 1931.

10 The use of continuous stationery wherein a succession of printed writing forms are detachably connected end to end in continuous supply strips which are superposed one upon another and interleaved with continuous strips of "one time" carbon material for manifolding purposes has become quite common.

It is generally recognized that however carefully and accurately such strips may be printed, when superposed one upon another they will not 20 register throughout, but require a slight degree of relative adjustment simultaneously with their feeding movement to maintain their registry at the writing position.

The ordinary friction feed typewriter mechanism will not maintain the registry of such superposed forms during the feeding operation.

The present invention pertains to the provision of retracting feeding pins in the periphery of a platen roll which, as the roll rotates, are automatically extended and retracted in sequence 30 whereby the punched manifolding strips will be engaged by the pins only at the writing line or closely adjacent thereto and will be automatically stripped from the pins by withdrawal of the latter without strain or disturbance after passing the writing position.

The superposed strips are thus left free to adjust relative to each other as they approach the writing position, and punched carbon material 40 may be successfully fed without undue strain, and transverse division lines of the carbon material can be maintained in accurate registry with those of the record strips at the "tear off" point.

This construction enables the substitution of the pin feed platen roll in standard types of typewriters as the feeding pins, being subject to retraction about the roll except adjacent to the writing line, avoid interference with the usual 45 friction or pressure roll and other parts of the machine adjacent to the platen roll.

Furthermore in the present construction means is provided for retracting the feeding pins at the writing line at will and thus enabling the typewriter to be used in the ordinary manner 55 merely as a friction feed mechanism.

The object of the invention is to simplify the construction as well as the means and mode of operation of pin wheel feed devices as applied to typewriters wherein the record and manifolding material circumferentially conform to the plat-

en roll, whereby they will not only be cheap and economical in construction, but will be more efficient in use, automatic in action, uniform in operation, of sturdy construction and unlikely to get out of repair.

A further object of the invention is to provide for automatic adjustment of superposed manifolding strips as they travel about a platen roll, to a considerable arc of which they conform.

A further object of the invention is to enable 10 the feeding of a large number of superposed apertured strips in accurate registry at the writing line, the apertures of which are offset relative to each other due to the travel of the strips about the platen roll in paths of different diameter. 15

A further object of the invention is to provide means for uniformly and smoothly stripping the 20 engaged strips from the feeding pins without the necessity of special stripping devices, and without strain upon or disturbance of the uniform movement of the strips.

A further object of the invention is to provide 25 pin wheel feeding means which will successfully feed punched carbon sheets interleaved between the record sheets without undue strain thereon, and without tearing or other mutilation, and which will automatically maintain the registry 30 of the carbon sheets with over and under-lying record sheets.

A further object of the invention is to provide 35 retractable feeding pins which will be automatically extended and retracted as the platen roll is rotated whereby the pins will engage with the punched paper only at, or closely adjacent to the writing line and wherein the pins will be retracted when passing adjacent parts of the mechanism and hence avoid interference therewith.

A further object of the invention is to provide 40 a pin feed platen roll which can be readily and easily substituted for the usual platen roll of standard typewriting machines.

A further object of the invention is to provide 45 control means for the retractable feeding pins whereby the pins may be retracted at the writing point and adjacent thereto, or the protruding pins shifted to an inoperative portion of the roll area wherein they will not engage with the paper supply and thus afford a smooth working 50 area of the platen for the usual friction feed operation and enabling the use of unpunched paper upon the same platen roll.

A further object of the invention is to automatically prevent the operation of the friction feed mechanism while the pins are feeding the 55 paper.

With the above primary and other incidental objects in view, as will more fully appear in the specification, the invention consists of the features of construction, the parts and combina- 60

tions thereof and the mode of operation, or their equivalents, as hereinafter described and set forth in the claims.

Referring to the accompanying drawings 5 wherein is shown the preferred, but obviously not necessarily, the only form of the embodiments of the invention, Fig. 1 is a perspective view of the traveling carriage of a popular type of writing machine in which the pin feed platen, 10 forming the subject matter hereof, has been substituted for the standard platen roll. Fig. 2 is a side elevation of the platen roll removed from the typewriter. Fig. 3 is a longitudinal sectional view of the pin feed platen roll. Fig. 4 is a transverse sectional view through the typewriter carriage showing the parts adjusted for pin feed operation. Fig. 5 is a similar view wherein the parts are shown relatively positioned for friction feed operation. Fig. 6 is a transverse sectional 15 view of the platen roll. Fig. 7 is a detail view of the actuating cam removed from the platen roll. Fig. 8 is a detail face view of the platen roll head showing the pin groove for guiding the pins radially as they travel about the cam. Figs. 9 and 10 20 are detail views of the alternating mechanism for friction and pin feed operation. Fig. 11 is a detail view of a modification of the pin adjusting means. Fig. 12 is a detail view of a pin. Fig. 13 is a further detail view. Figs. 14-16 inclusive show 25 detailed views of the platen control mechanism. Fig. 17 is a fragmentary end view with parts broken away showing the automatic control mechanism of the friction feed device.

Like parts are indicated by similar characters 30 of reference throughout the several views.

While the platen roll, forming the subject matter hereof, has been illustrated in the drawings as embodied in a particular make of typewriter, it is to be understood that the present pin feed 40 platen roll in proper size is interchangeable with the platen roll of substantially all standard makes of typewriters. To this end the present pin type platen roll simulates the proportions of standard typewriter rolls and employs the same mounting 45 and occupies the same relation to the various operating parts of the typewriting machine, and is actuated by the usual pawl and ratchet mechanism.

Referring to the accompanying drawings, 50 indicates an ordinary typewriter of which 2 is the reciprocating platen carriage, and 3 is the platen roll revolvably mounted in the platen carriage in the usual manner. The platen roll comprises a supporting shaft 4 which is revolvably mounted in 55 suitable bearings in the typewriter carriage from which the original friction feed platen roll has been removed. The shaft 4 carries at each end the usual knobs 5 by which the platen may be manually rotated.

Concentrically surrounding the shaft 4 is a cylinder 6 which may be rubber covered as is usual in typewriter constructions, but for manifolding purposes for which the present feeding mechanism is especially adapted, such cylinder 65 may be of metal to afford a harder abutment or contact surface for the impingement of the typewriter type. The cylinder 6 is fixedly connected to the shaft 4 for unison rotation therewith by a head 7, pressed, brazed or otherwise secured 70 in one end of the cylinder 6, and immovably mounted upon the shaft 4 by means of the set screw 8. Obviously other methods of mounting may be utilized. The cylinder 6 is further supported by additional heads 9-9 secured interiorly 75 of the cylinder 6 and journaled upon a tubular

sleeve 10 surrounding the supporting shaft 4. The sleeve 10 is preferably bushed at each end as at 11 to afford a journal bearing about the shaft 4.

The bearing bushing 11 of the tubular sleeve 10 upon the shaft 4, and the journal bearing of such sleeve 10 within the cylinder head 9 enables a rotary or rocking adjustment of the tubular sleeve 10 within the cylinder independently of the cylinder 6 and of the supporting shaft 4.

As illustrated in Fig. 8 the lateral faces of the cylinder head 9 are radially grooved at 12 to provide guide ways for reciprocating feeding pins 13 mounted therein, which in their outward lineal travel are projected beyond the periphery of the cylinder 6 through circumferentially spaced holes 14 each of which registers with a guide groove 12 in the head 9. The heads 9 are preferably flanged at 15 and provided with holes registering with the guide groove 12 and with the cylinder holes 14 thus forming a bearing surface entirely around each pin.

The pins 14 are tapered or pointed at their outer extremities to facilitate their engagement in the punched holes or apertures of punched paper with which the present platen is to be employed. The pins are also provided with lateral notches 16 for engagement over the lateral flange of a box cam 17. There is a box cam 17 adjacent to each of the pin carrying heads 9. 30 These box cams 17 are pinned or otherwise fixedly secured to the lock sleeves 10-10. As illustrated in Figs. 6 and 8 the cam 17 engaging within the lateral notches 16 of the pins is of eccentric formation, and as the pins travel about such cam 35 which is normally held stationary during the rotation of the cylinder, the pins are automatically reciprocated in their bearings in the heads 9. As the pins approach the extended portion 17a 40 of the cam in their rotary travel, the pointed ends of the pins are projected beyond the periphery of the cylinder 6 and into engagement with the paper webs extending about the platen roll. As the pins pass beyond the portion 17a, they 45 are automatically retracted, and during their travel about the concentric portion 17b of the cam, the pins are held in their inner position with their pointed ends retracted inwardly past the periphery of the cylinder and hence in inoperative relation and out of engagement with 50 the punched or apertured paper.

Normally the cam 17 is so positioned that its extended portion 17a agrees with the writing position so that the pins are projected outwardly as they approach the writing line and engage the 55 apertured paper only at the writing line and closely adjacent thereto, the pins being retracted as they move beyond the writing position. The automatic retraction of the pins serves to strip the apertured paper from the pins without the necessity of a stripper plate or other means for dislodging the paper from the pins as ordinarily employed in pin wheel feed devices. In typewriter constructions the record paper conforms closely to the platen roll throughout a very considerable circumferential extent usually approximating one-half to two-thirds of the circumference of the platen roll. It is quite impractical if not impossible to feed apertured paper or record strips over a pin wheel feed device throughout such extended contact line wherein the paper would necessarily engage a very considerable number of pins. There are several reasons for this difficulty, one of which is that the difference 60 between the points of the radially disposed pins 65

is somewhat greater than between the bases of the pins at the peripheral line of the pin wheel or roller. Consequently the engaging points are spaced apart a greater distance than the holes of the paper which are spaced to agree with the bases of the pins at the peripheral line of the pin wheel or roller. Therefore there is a considerable tendency to tear or mutilate the holes in the paper and a great deal of friction develops.

5 10 A further great difficulty arises from the fact that however carefully the paper may be printed and punched, slight inaccuracies of spacing of the holes and resulting lack of registry of the apertures or holes of different strips necessarily occur. When the holes of superposed apertured strips are in registry at one point, they are quite likely to be out of registry at other points only a few holes distance away and are certain to be out of registry when each sheet travels an increased circumferential distance around a cylinder platen. Consequently although the art shows platen rolls for typewriters having pin studs projecting in circumferentially spaced relation entirely about the circumference of the roll or wheel, such constructions have been found impractical and commercially inoperative in typewriters of the usual construction. These difficulties as well as others incident to the use of the pin wheel feed devices for standard typewriting machines have been overcome in the present construction by providing for the progressive projection and retraction of the pins as they approach and recede from the writing line or position upon the platen roll. While the extended portion 17a of the cam may be made of any suitable extent, the preferable construction is one wherein only one or not more than two pins 13 are in fully extended position at one time while an additional pin is being projected outwardly and another pin being simultaneously retracted as is illustrated in Fig. 6. This progressive extension and retraction of the feeding pins is of material advantage and especially so in adapting a pin feed platen roll to standard typewriter construction. The ordinary typewriter construction approaches quite closely to the surface of the platen roll and does not provide the necessary clearance for the projecting ends of the pins, if the pins are to remain extended throughout their entire path of travel. In the present construction, however, the pins are automatically retracted after performing their feeding operation and before they reach any interfering part of the typewriter construction. They are held in such retractive position entirely within the circumference of the platen roll until they again approach the writing position when they are extended into operative engagement with the apertured paper. Thus the pins being retracted clear, without interference, all associated parts of the typewriter construction including the usual pressure roller employed in standard typewriters for friction feed operation. The pressure roller 18 in the standard typewriter construction is adjustable toward and from the platen roll and when used for friction feeding of the paper supply it bears against the paper gripping the latter between the pressure roller 18 and the platen roll to advance the paper as the latter rotates. Although the pressure roller 18 is located in such position that there is no interference with the feeding pins 13 which are not projected beyond the periphery of the platen roll until they have passed beyond the position of the pressure roller 18, the pressure roller 18 is held out of contact with the paper and out of operative relation with the platen roll when the feeding pins 13 are employed. Pin wheel feed operation and friction feed operation are inconsistent with each other and, although there is no physical interference between the feeding pins and the pressure roller in the present construction, they can not be used simultaneously with any great degree of success. One of the advantages of pin wheel feed devices 10 is the capability of relatively adjusting the record strips to maintain accurate registry of printed forms and also registry of the tear-off lines of both the paper and the interleaved carbon material when used. If the superposed record strips 15 are confined by the pressure roller 18 while being engaged and fed by the feeding pins 13, the superposed strips are not free for relative adjustment as succeeding holes or apertures are engaged by the pins and consequently the holes will not exactly register with each other or with the pins and the paper will be torn. The friction or tension imposed upon the strips by the pressure roller when engaged with the paper defeats the dominant purpose of the feeding pins. Consequently when the pins 13 are employed for feeding and alining the superposed strips of material, the pressure roller 18 is disengaged from the platen roll and is held in an inoperative spaced relation with the platen roll by the adjusting 20 means ordinarily provided on every standard typewriter. This adjusting means for the pressure roll is controlled by a finger lever 19 on the carriage, which when depressed, moves the pressure roller 18 away from the platen roll and holds 25 it in such position until the lever 19 is again elevated.

25 30 35 40 45 50 55 60 65 70 75 In order that the typewriter may be used in the usual manner, employing the pressure or friction roller 18 for frictionally feeding the paper about the platen roll, means is provided for shifting the feeding pins 13 to an inoperative position. It is for this purpose that the tubular sleeve 10 is journaled for rocking adjustment about the shaft 4 and within the cylinder heads 9. By 40 rocking the tubular sleeve 10, the control cams 17 fixedly attached thereto are also turned relative to the platen roll to such position that the pins 13 are held retracted as they pass the entire area contacted by the paper strips which conform to 45 the periphery of the roll and are projected beyond the periphery of the roll only in an inoperative position beyond the writing line where they clear the paper strips. Such inoperative position of the cam 17 is shown in Fig. 6. To rock the 50 sleeve 10 and with it the cams 17 to change the operative position of the pins relative to their path of travel, a manually operable lever arm 20 is provided at the end of the cylinder and secured to the extremity of the tubular sleeve 10. This 55 lever arm projects above the level of the platen roll and is easily accessible by the operator for swinging movement in a fore and aft direction thereby giving to the sleeve 10 and the cams 17 60 partial rotation. Any sort of detent means may be employed for locking the lever 20 in its adjusted position and so holding the cams 17 immovable while the roll or cylinder rotates thereabout. In the drawings this detent has been 65 illustrated as a slotted bar 21 having therein notches in which a stud 22 upon the shift lever 20 is engageable to hold the cams 17 in different positions of rocking adjustment.

70 75 In lieu of the lever locking detent there is

illustrated in Figs. 9 and 10 a safety or "fool proof" means which prevents the simultaneous operative engagement of the friction feed rollers and the pins with the manifolding strips. In this construction the adjusting lever 20 is formed with a segment 23 which is positioned beneath a projecting stud or screw head 24 upon the crank arm 25 by which the friction rollers are shifted into and out of operative engagement with the platen. The segment 23 is of such length that it prevents the depression of the crank arm 25 until the segment 23 is moved to an extreme position in which it passes beyond the path of movement of the stud or screw head 24. The segment 23 is provided with a notch 26 in which engages a pivoted detent member 27 mounted upon one of the platen carriage rods 28 of the typewriter and drawn into engagement with the periphery of the segment 23 by a spring 29, one end of which connects with the detent 27 and the other end of which is connected to the segment 23. The detent 27 is provided with a trip finger 30. When the adjusting lever 20 is drawn to a forward position thereby turning the actuating cam to such position that the feeding pins are projected beyond the periphery of the platen roll in proximate relation with the writing line, the detent 27 drops into the notch 26 and thereby locks the segment and adjusting lever 20 in their forward position. In this position of adjustment the segment 23 extending beneath the stud or screw head 24 in the crank arm 25 prevents adjustment of the friction rollers. However, by merely touching the upstanding strip finger 30 of the detent the latter is raised from the notch 26 and the spring 29 operates to throw the segment 23 rearwardly out of the path of the stud or screw head 24 thereby turning the actuating cams and causing the pins to be retracted at the writing position and to be projected only at an inoperative position. The movement of the segment 23 leaves the crank arm 25 free for oscillatory movement to adjust the friction rollers into operative relation with the platen.

While as before stated the platen roll herein described is intended to be interchangeable with the ordinary platen of any standard typewriter, when made of corresponding size, it is not limited to such substitute use but may be embodied in other writing machines such as automatic recording apparatus, billing machines, computing machines, autographic registers and various other installations employing continuous web paper supply. The radially disposed reciprocating feeding pins are preferably, though not necessarily, arranged in two spaced rows. They may, however, comprise either a single series or multiple series and may be projected beyond the periphery of the roll at any circumferential point but preferably at a point in proximate relation to the writing line in which the type strike upon the paper about the platen at which point registration is required. By revolubly adjusting the position of the actuating cams about which the pins are carried by the rotation of the platen, the selected position in which the pins project may be changed at will. Being retractive at all points except the selected position, the pins avoid interference with adjacent structural parts of the typewriter. The construction permits the use of the ordinary friction feed device for advancing the paper to position in which it is engaged by the pins when loading the machine.

It also provides an interlocking arrangement whereby the friction feed rollers are maintained in non-operating position when the feeding pins are engaged with the paper and vice versa. This construction enables the use of interleaved carbon paper punched similarly to and of full width of the manifolding form which has heretofore been impractical. It also enables the use of tabbed carbon paper to facilitate the separation of the interleaved carbon sheets from the record sheets after separation from the supply strips and further enables the use of interleaved punched carbon paper which is unglued or unattached to the printed form as has heretofore been the custom to prevent side shifting. The rectilinear movement of the feeding pins into and out of the platen has much greater alining capacity as to the number of copies of manifolding forms that can be properly fed and permits the use of platens of small diameter without the difficulties encountered in ordinary radial pin constructions wherein the pins enter and leave the feed holes in a lateral or swinging movement thus requiring greater clearance or variation of size between that of the holes and the pins. It further obviates the necessity for stripper devices since the pins are automatically withdrawn from the paper at the proper points.

In the present construction registration is attempted upon substantially a single line only, or in any event throughout only a very small portion of the circumferential arc of the platen roll. When it is attempted to feed punched paper circumferentially about a platen roll having fixed radial feeding pins, as distinguished from feeding the material tangentially past the pin wheel feed devices, the discrepancies occurring in the relative spacing of succeeding printed forms and between succeeding feeding apertures as well as the relative displacement of forms and apertures of different strips, due to the travel of succeeding strips through paths of increased diameter are distributed substantially equally between the number of pins engaged in the paper at the same time. Thus in such construction the multiple fixed pins, by their engagement with the strips, actually prevent proper registration of superposed forms and accurate alinement at the writing position is quite impossible.

In standard types of typewriters which depend solely upon friction feed means for advancing the record material, means is provided for releasing the friction feed devices to enable the paper or other record material to be adjusted relative to the platen roll to register the writing line upon the record sheet or upon a printed form with the writing position of the platen. Obviously such relative adjustment of punched forms adapted for pin wheel feed devices is quite impossible. The necessity, however, remains for properly alining or registering the writing lines of printed forms and the like with the point of impact of the typewriter type. In many standard makes of typewriters there are embodied line locating means which generally consist of some friction clutch or similar device for disconnecting the line spacing and feeding ratchet of the platen roll from the body of the roll or from other paper feeding devices which may be employed. Inasmuch as it is quite impossible to shift the paper relative to the roll in a construction wherein rotary pin feed devices are employed the pins of which enter apertures in the record material, it is necessary to change or readjust the

relative position of the pin carrying platen to that of the feeding ratchet in order that the typewritten impressions may appear in proper relation with lines upon the printed form.

5 As is illustrated in the detail view, Fig. 13, there is shown a friction clutch which adjustably connects the line spacing ratchet wheel 31 with the platen roll and comprises a male member 32 spring pressed into the female portion 33 of the clutch, the contacting surfaces being provided with friction material coating or with fine line knurling so that they may be fixedly interengaged with each other in different positions of revoluble adjustment to maintain the selected relation of 10 the ratchet wheel and platen roll. By releasing the friction clutch members 32 and 33 the pin carrying roll may be adjusted revolubly relative to and independent of the line spacing ratchet 31. This enables the lines of a printed form to be adjusted to proper registry with the impact point 15 of the typewriter type.

A typical construction is illustrated in Figs. 13 to 16 inclusive wherein the male member 32 of the clutch is slidingly mounted upon the shaft 25 of the platen roll and may be retracted against the tension of a helical spring 34 out of engagement with the female member 33 of the clutch. The female member 33 is fixedly connected with the ratchet wheel 31 and loosely journaled upon the platen roll shaft except for its connection therewith through the interengagement of the clutch members 32 and 33. The member 32 is provided with an enlargement or knob 35 having 30 therein a slot 36 in which slidingly engages the key lug 37 on the collar 38. The latter is secured upon the platen roll shaft and serves to couple the clutch members therewith for unison rotation but permits axial sliding movement of the clutch member 32 into and out of engagement with the member 33. In Fig. 16 there are shown the actuating pawl 39 for operative engagement with the ratchet wheel 31 and also a detent 40 engaging with the ratchet wheel 31 to retain it in its 35 adjusted position. This construction of the line adjusting means is herein shown and described for illustrative purposes only and does not, per se, form any part of the present invention except so far as it is interrelated with the operation of pin feed mechanism.

50 In order that the punched paper may be supplied uniformly to the platen roll throughout the range of travel of the typewriter carriage, and to insure against such binding or straining of the supply material as would interfere with free movement of the paper onto and off the feeding pins and the relative adjusting movement necessary for maintenance of proper registration, it is desirable that the supply of material be conducted 55 to the platen roll over a suitable guide device as is shown in Fig. 1 which may be stationarily located in distantly spaced relation with the roll as may also be located the supply packet or roll of manifolding material. However, the preferable method of supplying material is to provide a traveling carrier operatively connected with and actuated to and fro in unison with the platen carriage. Such traveling carrier 50 may be mounted 60 independently of the typewriter, or may be supported directly upon the typewriter frame. Such traveling carrier 50 constructions are fully shown and described in copending applications, Serial No. 460,764 and Serial No. 519,488 to which reference may be had for detail description, such con-

structions forming no part of the present invention, *per se*, except so far as it is related to the feeding operation of the present pin type platen roll and hereinafter claimed in combination therewith.

5 In the modification disclosed in Fig. 1, the carrier 50 is carried by the carriage 2 through the arms 52 so that as the carriage 2 is actuated to and fro in the typewriter, the paper supply carrier 50 moves in unison therewith.

10 A means for holding the punched manifold paper webs in feeding position with the pins without the use of frictional feed has been disclosed in Fig. 1 and includes pivotally mounted arms 54 carried on a cross rod 56 that in operative position 15 as disclosed to the left of Fig. 1, has a curved surface 58 that follows the contour of the roll to hold the record material in contact with the pins.

15 The above described mechanism is shown in my co-pending application, Serial No. 542,855, for a Pin feed platen roll, filed on June 8, 1931.

20 Referring to Fig. 17, another modification is shown of the safety or fool-proof means which prevents the simultaneous operative engagement 25 of friction feed rollers and with pins with the manifolding strips. The tubular sleeve 60 carries a cam sector 62 having the full line position when the feeding pins are in operative position and having a dot-dash position when the pins are in 30 inoperative position. This cam 62 when the pins are in operative position shifts the friction rollers 18 out of engagement with the platen. When this cam is rotated to dot-dash position the friction rollers are free to move into engagement with the platen. A pair of notches 64 cooperate with 35 the detents 66 in holding the cam sector in either position, it being necessary to move the detent 66 out of engagement with the cam sector when shifting the pin feed mechanism from one position to the other.

40 From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its 45 advantages.

50 While in order to comply with the statute the invention has been described in language more or less specific as to structural features, it is to be understood that the invention is not limited to the specific features shown, but that the means 55 and construction herein disclosed comprise the preferred form of several modes of putting the invention into effect and the invention is therefore claimed in any of its forms or modifications within the legitimate and valid scope of the appended claims.

55 Having thus described my invention, I claim:

1. A platen roll for a writing machine, a plurality of retractable feeding and aligning pins carried by the roll, means for progressively extending and retracting the pins responsive to the rotation of the roll, and means for shifting the position of greatest projection of the pins circumferentially of the roll.

60 2. A platen roll for a writing machine, a plurality of retractable feeding and aligning pins carried by the roll, means for progressively extending and retracting the pins responsive to the 65 rotation of the roll, and means for shifting the 70 position of greatest projection of the pins circumferentially of the roll.

75

position of greatest projection of the pins toward and from the writing line upon said platen roll.

3. In a typewriting machine, a platen roll, a pin feed device for feeding a web of punched record material circumferentially about the roll comprising a plurality of feeding and aligning pins mounted radially in said roll for reciprocatory motion and adjustable means operative upon rotation of the platen roll to project and retract said pins progressively whereby a portion only of the pins carried in that portion of the platen roll to which the record web conforms will be projected into engagement therewith.

4. A feeding device for a continuous strip or strips of punched record material, including a rotary carrier, a plurality of reciprocatory feeding pins radially mounted in the carrier, and actuating means progressively projecting the pins outwardly and positively retracting the projected pins inwardly in sequence responsive to the rotation of the carrier, and control means for varying the points in the path of the rotary carrier at which the pins are projected and retracted.

5. A feeding device for feeding a continuous apertured strip or strips, including a rotary carrier, a plurality of reciprocatory feeding pins radially mounted with respect to the carrier, and actuating means for progressively projecting said pins outwardly and positively retracting them inwardly by the rotation of the carrier, the actuating means being adjustable to vary the positions in the path of the carrier at which the pins are projected and retracted.

6. In a feeding device for an apertured web, including a rotary carrier about which the web is fed in circumferential relation, a plurality of reciprocatory feeding pins carried thereby, and control means for progressively projecting the pins beyond the periphery of the carrier into feeding engagement with the web as the pins approach a predetermined point in the travel of the carrier and for thereafter progressively and positively retracting the pins after passing such point and adjusting means for varying the position of such operative action of the pins.

7. In a feeding device for an apertured web, including a rotary carrier about which the web is fed in circumferential relation, a plurality of reciprocatory feeding pins carried thereby, and control means for progressively projecting the pins beyond the periphery of the carrier, and retracting the pins responsive to the rotation of the roll, and an adjustable friction roll engageable with the web on the roll in the plane of rotation of the pins.

8. In a platen roll for writing machines, a series of movable feeding pins for operative engagement with punched record material to feed the same circumferentially about the roll, said pins being radially disposed about a common axis, actuating means for progressively advancing and retracting the pins radially responsive to the rotation of the platen roll, and manually operable adjusting means for circumferentially changing the position at which the pins are projected to their extreme position.

9. In a platen roll for writing machines, a series of movable feeding pins for operative engagement with punched record material to feed the same circumferentially about the roll, said pins being radially disposed about a common axis, actuating means for progressively advancing and retracting the pins radially responsive to the rota-

tion of the platen roll, means for circumferentially changing the position at which the pins are projected to their extreme position, a friction roll operatively engageable with the record material about the platen roll and control means permitting the operative engagement of the friction roll only when the feeding pins are adjusted for projection to extreme degree in an inoperative position.

10. In a platen roll for writing machines, a series of radially movable feeding pins for operative engagement with punched record material to feed the same circumferentially about the roll, said pins being radially disposed about a common axis, actuating means for progressively advancing and retracting the pins rotating in unison with the rotation of the platen roll, means for circumferentially changing the position at which the pins are projected to their extreme position, a friction roller operatively engageable with the record material upon the platen roll, the feeding pins and the friction roll being alternately adjustable to operative relation with the record material about the platen roll.

11. In a platen roll for writing machines, a series of movable feeding pins for operative engagement with punched record material to feed the same circumferentially about the roll, said pins being radially disposed about a common axis, actuating means for progressively advancing and retracting the pins responsive to the rotation of the platen roll, means for circumferentially changing the position at which the pins are projected to their extreme position, a friction roll operatively engageable with the record material about the platen roll and control means preventing the adjustment of the friction roll into operative relation until the projection point of the pins has been changed to inoperative position.

12. The combination with a platen roll for a writing machine, of a series of feeding pins engageable with punched record material fed circumferentially about the roll, adjustable means for rendering the feeding pins inoperative at the will of the operator, a friction feed means for the record material, means for rendering the friction feed means inoperative, and interlocking means whereby only one of said feeding means may be in operative engagement with the record material at a given time.

13. The combination with a platen roll for a writing machine, of a series of feeding pins engageable with punched record material to feed the same circumferentially about the roll, adjustable means for rendering the feeding pins inoperative at the will of the operator, a friction feed means for the record material, means for rendering the friction feed means inoperative, and alternating means for effecting alternate operative engagement of the respective feeding means with the record material.

14. The combination with a platen for a writing machine, of a series of feeding pins associated therewith for operative engagement with punched record material fed over said platen, operating means for effecting progressive extension and retraction of the pins beyond the surface of the platen, and adjusting means for changing the position at which the pins are projected and retracted relative to the writing position upon said platen.

15. The combination with a platen for a writing machine, of a series of feeding pins associated therewith for operative engagement with punched

record material fed over said platen, operating means for effecting progressive extension and retraction of the pins beyond the surface of the platen, the writing position upon the platen and the positions at which the pins are projected and retracted being relatively variable and adjusting means therefor.

16. A writing machine platen, a rotary series of reciprocatory feeding pins for operative engagement with punched record material to feed it over the platen, said pins being radially disposed about a common axis, actuating means for progressively projecting and positively retracting the pins beyond the surface of the platen in unison with the rotation of the series of pins, and adjusting means for changing the position at which the pins are projected and retracted relative to the platen.

17. A platen roll for a writing machine, a plurality of retractable feeding pins carried by the roll, means for holding punched manifoldded paper webs in feeding position over the pins without frictional feed, means for progressively extending and positively retracting the pins in unison with the rotation of the roll, and means for shifting the position of greatest projection of the pins toward and from the writing line upon said platen.

18. In a feeding device for an apertured web, including a rotary carrier about which the webs are fed in circumferential relation, a plurality of reciprocatory feeding pins carried thereby, and control means for progressively projecting the pins beyond the periphery of the carrier, and retracting the pins in unison with the rotation of the carrier, and an adjustable friction roll engageable with the web on the carrier in the plane of rotation of the pins, and means preventing the interference of the pins and friction roll one with the other.

19. In a platen roll for writing machines, a series of movable feeding pins for operative engagement with punched record material to feed the same circumferentially around the roll, said pins being radially disposed about a common axis, actuating means for progressively advancing and retracting the pins to operating and nonoperating positions, a friction roller operatively engageable with the record material upon the platen, the feeding pins and friction roll being alternately adjustable to operative relation with the record material about the platen.

20. In a platen roll for writing machines, a series of movable feeding pins for operative engagement with punched record material to feed the same circumferentially about the roll, said pins being radially disposed about a common axis, manually adjustable means for depressing the pins from contact with the paper at operating position, a friction roll operatively engageable with the record material about the platen roll and control means preventing the adjustment of the friction roll into operative relation until the pins have been depressed at the operating position.

21. The combination with a platen roll for a writing machine, of a series of equally spaced feeding pins engageable substantially at the writing line with punched record material fed circumferentially around the roll, means for making the pins inoperative at the writing line at the will of the operator and means for feeding the paper during the nonengagement of the pins.

22. The combination in a typewriter, a writing platen mounted therein, equally spaced feed pins

arranged to engage apertures in record material at a point contiguous to the writing point, means for retracting the pins from operative relation to the record material, means for advancing the feed pins to feed the record material for line to line writing and means for frictionally feeding the record material alternately with feeding operation by the feed pins.

23. The combination with a writing machine having a writing platen, of means for positively advancing apertured record material past the platen, including a traveling series of feeding pins of which a progressively changing plurality thereof have constant engagement within apertures in the record material during the feeding period of such pins, means for effecting travel movement of the pins while in engagement with the material to advance the record material past the writing platen, manually controlled means for rendering the feeding pins inoperative to advance the record material, and independently operable means for feeding record material past the platen independently of the action of the feeding pins when said pins have been rendered inoperative.

24. In a rotary platen typewriter machine, a platen around which record forms are circumferentially fed, feed pins mounted in a rotary carrier for continuously feeding said record forms in alignment past a writing point, said feed pins having operative and inoperative positions, means for advancing the pin feed means step by step for line spaced writing, auxiliary frictional feeding means for advancing the record forms and means for causing the frictional feeding means to become inoperative when the aligning pin feed means is moved into operative position.

25. A platen roll for a writing machine, a plurality of reciprocating feeding pins carried by the roll, means for progressively extending and retracting the pins responsive to the rotation of the roll, means for shifting the position of greatest projection of the pins circumferentially of the roll, and a lock for locking said shifting means in shifted position.

26. A platen roll for a writing machine, a plurality of groups of strip feeding and aligning pins mounted therein for reciprocatory motion, and cams with which the pins engage and about which they are caused to travel by the rotation of the platen whereby the pins are progressively advanced and retracted responsive to the rotation of the platen roll, at least one of said cams being mounted for to and fro rocking adjustment whereby the position of maximum projection of the pins beyond the periphery of the roll may be varied.

27. The combination with a platen roll for a writing machine, of a series of feeding pins having operative and inoperative positions, said pins when in operative position being engageable with punched record material fed circumferentially about the roll, means for circumferentially changing the operative position of the pins toward and from the writing line.

28. The combination with a platen roll for a writing machine, of a series of feeding pins having operative and inoperative positions, said pins when in operative position being engageable with punched record material fed circumferentially about the roll, the operative position of the pins being variable circumferentially of the roll, and means for maintaining the operative position of the pins in predetermined relation with the writing position.

29. In a typewriter, a rotary platen, non-fric-

- tion feeding means for feeding a web of material through indefinite distances, and friction feeding means adapted to be operated in connection with said rotary platen to feed said web, also indefinite 5 distances at the will of the operator and means preventing the operation of one feeding means while the other is in operation.
30. In a typewriter, two paper feeds optionally selective, one adapted when selected to feed continuous-form paper webs in registry with each other, the other adapted to feed said webs by a frictional non-registering feed, and control means preventing simultaneous operation of the two feeds.
- 15 31. In a typewriter, rotary optionally selective feeding means for positively maintaining manifold record forms in relative alignment while being fed, rotary feeding means for frictionally feeding the forms and common means compelling the separate operation of the two feeding means.
- 20 32. The combination in a typewriter, of two rotary feeding means selective optionally, one when selected adapted to feed superposed record forms in relative alignment with each other, the other adapted to feed the forms without aligning adjustment and means for preventing simultaneous operation of the two feeds.
- 25 33. In a writing machine, a rotary platen, a pin feeding mechanism of which the pins are movably associated with said platen, said pin feeding mechanism including a cam having a closed, loop-like cam surface for controlling the movement of the pins, said cam surface enclosing the center of rotation of said platen, and means for rotating said cam about said center.
- 30 34. A pin wheel feeding mechanism including a plurality of pins mounted for movement through predetermined paths, a cam having a closed, loop-like cam surface for controlling the path of said pins, and means for rotating said cam so as to change the path of said pins.
- 35 35. A pin wheel feeding mechanism for a writing machine, said pin wheel feeding mechanism having an operative and an inoperative position, said feeding mechanism including a plurality of movably mounted pins, and a cam having closed, loop-like cam surface for controlling the movement of said pins, said cam being pivotally and rotatably mounted so that as it is rotated about the pivot the feeding mechanism is changed from one position to the other.
- 40 36. In a pin wheel feeding mechanism having an operative and an inoperative position, a plurality of movably mounted pins radially disposed about a common center, a cam having a loop-like, closed cam surface enclosing said center, said cam controlling the movement of said pins, the cam being rotatively mounted about said center so as to shift the pin wheel feeding mechanism from one position to the other.
- 45 37. In a pin wheel feeding mechanism for a writing machine, a roller supporting the writing material, a plurality of movably mounted pins radially disposed with respect to said roller, a cam having a loop-like cam surface pivotally mounted on the axis of said roller for controlling the movement of said pins, and means for rotating said cam about said axis so as to change the pin wheel feeding mechanism from one position to the other.
- 50 38. In a writing machine having a writing position, a platen, a pin feeding mechanism associated with said platen, said pin feeding mechanism including reciprocatory pins extending beyond the periphery of said platen for a portion 55 of the circumference of the platen, and means for shifting the position of said portion with respect to the writing position.
- 5 39. In a writing machine, a roll, a pin feeding mechanism associated with said roll, said pin feeding mechanism including reciprocatory pins extending beyond the periphery of said roll for a portion thereof, and means for shifting the relative position of said portion with respect to the writing position of said machine.
- 10 40. In a writing machine, a platen, a pin feeding mechanism associated with said platen, said pin feeding mechanism including a cam having two positions, one of said positions guiding the pins in an inoperative path that is out of engagement with the writing material, and when in the other position guiding the pins in a path extending into engagement with the writing material so as to cause the writing material to be advanced by said pin feeding mechanism.
- 15 41. A platen roll for a writing machine, including a rotary cylinder, a plurality of groups of reciprocatory feeding pins mounted in said cylinder for projection and retraction past the periphery thereof, each group including an actuating cam therefor normally held stationary and about which the pins are carried in constant contact by the rotation of the cylinder, said cam being capable of to and fro rocking motion to vary the position in the rotary path of the cylinder at 20 which the pins are projected and retracted.
- 20 42. A platen roll for a writing machine, including a rotary cylinder, a supporting shaft therefor to which the cylinder is connected for unison rotation, a plurality of groups of reciprocatory pins mounted in the cylinder, a rock sleeve mounted upon the shaft within the cylinder, cams upon the sleeve with which the pins engage in their travel with the cylinder and by which the pins are given longitudinal motion, 25 and means for holding the rock sleeve in different positions of adjustment to effect longitudinal movement of the pins in different portions of their path of travel.
- 25 43. A platen roll for a writing machine, including a rotary cylinder, a supporting shaft therefor to which the cylinder is connected for unison rotation, a plurality of groups of reciprocatory pins mounted in the cylinder, a rock sleeve mounted upon the shaft within the cylinder, 30 cams upon the sleeve with which the pins engage in their travel with the cylinder and by which the pins are given longitudinal motion.
- 30 44. In a writing machine, frictional feeding rollers cooperating with a platen for frictionally feeding writing material, throwout means for rendering the friction feeding rollers ineffective, a platen roll interchangeable with the usual platen roll of a writing machine and including reciprocatory feeding pins radially disposed in groups 35 for positive engagement in series punched feeding holes in the writing material, means for effecting progressive reciprocation of the pins into and out of engagement with the writing material in unison with the rotation of the platen, throwout means for rendering the feeding pins ineffective, the writing material being fed at the will of the operator alternately by frictional engagement of the rollers and by positive engagement of the feeding pins in accordance with 40 the adjustment of the respective throwout means.
- 35 45. In a writing machine, the combination with friction rollers cooperating with a platen roll for frictionally feeding writing material and throwout means for rendering the friction rollers ineffectual.

- fective, of a pin type platen roll, selective feeding members carried thereby for engagement in series punched holes to positively feed the writing material when selected, and control means for rendering the feeding members ineffective, the friction rollers and the feeding members being alternately usable at the will of the operator for feeding the writing material.
46. A writing machine including a platen roll and friction rollers cooperating with the platen roll for frictionally feeding writing material thereabout, throwout means for rendering the friction rollers inoperative, retractable feeding pins carried by the platen roll engageable with the writing material for positively feeding the material independently of the said frictional feeding means, and manually operated throwout means for rendering the feeding pins inoperative, said frictional and positive feeding means being usable alternatively at the will of the operator but not simultaneously.
47. In a writing machine having frictional feeding means for writing material, and throwout means for rendering such frictional feeding means inoperative, an additional feeding means selective for positively feeding the writing material independently of the frictional feeding means, said additional feeding means including a pin feeding device having operative and inoperative positions, and throwout means for moving the positive feeding means into inoperative position.
48. The combination with a writing machine having friction rollers coacting with a platen roll for frictionally feeding writing material about the platen roll and throwout means for rendering the friction rollers inoperative, of a second pin type platen roll interchangeable with the original platen roll, including retractable pins for feeding engagement with series punched holes in the writing material for positively feeding the writing material, and adjusting means for rendering the feeding pins ineffective, said roller throwout means and pin adjusting means being alternately operable to enable alternate feeding of the writing material frictionally and positively about the same platen roll.
49. The combination with a writing machine wherein a pin type platen roll for positively feeding writing material through the machine is interchangeable with an original friction type platen roll and including friction rollers operable in coacting relation with either of the platens, and throwout means for rendering the friction rollers inoperative, of a pin type platen roll, a plurality of retractable feeding pins carried by the platen roll, actuating means for progressively projecting the pins into feeding engagement with series punched holes in the writing material, and control means for the pins for rendering the pins ineffective, said control means and roller throwout means being independently operable alternately to enable alternate frictional and positive feeding of the writing material.
50. In a writing machine, frictional feeding rollers cooperating with a platen roll to frictionally feed writing material, a platen roll with which the rollers cooperate, a series of retractable and extensible feeding members carried by the platen roll and progressively projected into and retracted out of positive engagement with the writing material in unison with the rotation of the platen roll, and manually controlled individual throwout means for conversely rendering the frictional feeding rollers and the retractable feeding members effective and ineffective alternately.
51. In a writing machine, frictional feeding rollers cooperating with a platen for frictionally feeding writing material, a platen roll with which the frictional rollers cooperate, retractable feeding pins arranged in groups and progressively projected peripherally beyond and then retracted within the platen roll in unison with the rotation thereof, independently operable throwout means for the frictional feeding rollers and the retractable feeding pins for alternately rendering one effective and the other ineffective and vice versa, whereby the material may be fed either frictionally or positively at the will of the operator.
52. The combination with a writing machine, a rotary platen supporting the record material passing circumferentially, a series of reciprocatory material feeding and aligning pins carried thereby for continuously feeding record material, said aligning pins traveling in a direction coincident with the radius of curvature of the record material at the point of engagement, and means for causing the pins to intersect the surface of the platen, said means having an inoperative position whereby in inoperative position the pins do not engage the record material.
53. A platen roll for a writing machine, and a series of adjustable tapering feeding and aligning pins mounted in the roll and adjustable control means for advancing and retracting the pins at circumferentially variable positions, said pins rotating in unison with the rotation of the roll to feed the record material and align the same when in writing position.
54. In a writing machine, two optionally selective paper feeding devices, including a rotary pin wheel type feeding device engageable when selected in marginally punched apertures in record material for positively feeding the record material past a writing position and a frictional feeding device engageable with the record material alternately with the engagement of the pin type feeding device, for impositively advancing record material past the writing position, and common drive means for actuating the positive and impositive feeding devices.
55. In a writing machine, rotary optionally selective pin type feeding device engageable in successive registering holes in superposed strips of record material for advancing manifolding forms past a writing position in relative registry and alignment, and rotary feeding means including a pressure roller frictionally engageable with the record material for feeding record material past writing position alternately with the pin type feeding device, and drive means for said feeding devices.
56. The combination with a platen roll for a writing machine having a writing position of optionally selective record material feeding means therefor, including a series of equally spaced traveling feeding pins engageable with series punched holes in record material to positively feed the material circumferentially about the platen roll and past the writing position during periods of nonfeeding engagement of other feeding means and a frictional pressure roller cooperating with the platen roll to feed record material circumferentially about the platen roll and past the writing position when out of operative engagement by the feeding pins, said friction roller and traveling pins being actuated by rotation of the platen roller.

57. The combination in a writing machine, a writing platen mounted therein, a rotary pin wheel feeding device including equally spaced feed pins arranged to engage spaced apertures in 5 record material for positively feeding the material past the writing platen, the record material and pins being optionally engageable and disengageable at the will of the operator, means for rotating the pin wheel device for advancing the 10 feed pins to feed the record material for line to line writing, and a pressure roller engageable with the record material at the will of the operator for feeding record material past the writing platen alternately with feeding operation thereof 15 by the feeding pins.

58. In a writing machine, optionally selective dual record material feeding means for feeding superposed manifolding record forms, including feeding means having positive engagement with 20 the record material when selected, adapted to feed superposed record forms in relative alignment with each other, and a frictional feeding means adapted when selected for feeding the forms without aligning adjustment, the respective feeding 25 means being each engageable with the record material for feeding operation at the will of the operator to the exclusion of the other feeding means.

59. A writing machine wherein dual record material feeding means is operable to alternately advance record material positively and impositively past a writing position, characterized by a series 30 of traveling feeding pins of which a progressively changing plurality have progressive feeding engagement with apertures in the record material 35 to positively advance the record material exclusively of the other feeding means past the writing position during periods of operation of indefinite duration, means for rendering the feeding pins 40 impotent to advance the record material at the will of the operator, and a second feeding means frictionally engageable with record material for advancing the record material exclusively of the feeding pins past the writing position through 45 periods of indefinite duration during periods of inaction of the feeding pins, the record material being operatively engageable with either of the respective feeding means at the will of the operator, to the exclusion of the other feeding means.

60. A dual feed writing machine wherein record material is progressively advanced past a writing position by frictional pressure rollers cooperating with a rotary platen roll, said frictional feeding devices being temporarily rendered inoperative 55 by throw out means, characterized by a pin wheel feeding device for positively feeding record material past the writing position alternately with the feeding operation of said frictional devices, including feeding pins progressively engageable 60 in marginally punched apertures in the record material to advance the same past the writing position during periods of inoperation of the frictional feeding devices, and actuating means common to the friction rollers and pin wheel feeding 65 devices.

61. A dual feed writing machine wherein record material is progressively advanced past a writing position by frictional feeding means capable of being temporarily rendered inoperative, 70 characterized by pin type feeding means for pro-

gressively advancing record material past the writing position, wholly independently of the frictional means, the frictional and pin type feeding means being disposed one in advance of the other in the path of travel of the record material whereby such material idly passes one of said feeding means in its progress into feeding engagement by the other feeding means, either of the feeding means being engageable with the record material independently of the other at the will 10 of the operator whereby the record material will then be progressively advanced past writing position wholly by the action of only one of said feeding means.

62. In a dual feed typewriting machine a pair 15 of spaced pin wheel feeding devices having disappearing pins about which record material is fed circumferentially past a writing position by the engagement of the pins in the marginally punched apertures in the record material when said pins 20 are extended in feeding position, a platen disposed between the wheels and substantially coincident with the peripheries thereof and frictional feeding rollers engageable with the record material for feeding the record material past the writing 25 position when the pins are retracted the frictional rollers being operable alternately with the feeding pins for advancing the record material and means by which the pins may be retracted from feeding relation with the material preparatory 30 to feeding operation of said rollers.

63. The combination with a writing machine of the type having frictional feeding means wherein pressure rollers coact with a platen roller for frictionally feeding record material past 35 a writing position, of a substitute positive feeding means for the record material, including a pin type platen roll and mounting means therefor interchangeable with those of the original frictional feeding means, feeding pins carried by the 40 platen progressively engageable in punched holes in record material for positively advancing the material past the writing position in lieu of the frictional feeding means, frictional feeding means for feeding record material past writing position 45 during periods of nonfeeding operation of the pins and supporting means on the writing machine common to the original and substitute platens and their mounting means.

64. A writing machine adapted for frictional 50 feeding of record material wherein pressure rollers cooperate with a rotary platen roll to advance the record material past a writing position, said platen roll being provided with mounting means removable from the writing machine, 55 characterized by a substitute pin type platen roll and mounting means therefor interchangeable with the frictional rotary platen and removable mounting means aforementioned, feeding pins carried by the substitute platen roll engageable 60 in marginally punched holes in the record material for positively advancing the material past the writing position in lieu of said frictional means, pressure rollers with which the pin type platen may cooperate at will of the operator to frictionally feed the record material in lieu of the feeding pins and supporting means on the writing machine adapted to receive the respective platen rolls and mounting means interchangeably.

JOHN Q. SHERMAN. 70
